HARVEY CLAYTON RENTSCHLER, OF EAST ORANGE, NEW JERSEY, ASSIGNOR TO
WESTINGHOUSE LAMP COMPANY, A CORPORATION OF PENNSYLVANIA.

HIGH-FREQUENCY LAMP.

Application filed February 21, 1923. Serial No. 620,353.

This invention relates to incandescent lamps, more especially to lamps adapted for use in concentrating light upon an object, such as in motion picture projectors, search lights and the like.

It is an object of my invention to provide an incandescent lamp having a refractory body adapted to be heated by an arc or electrical discharge generated by high frequency alternating currents or high frequency electrical oscillations.

Another object of my invention is the provision of an incandescent lamp having two disks of refractory material arranged parallel and which are adapted to become incandescent by an arc or electrical discharge operated between the same.

Another object of my invention is to provide an incandescent lamp having electrodes therein which are brought to incandescence by an arc or electrical discharge playing between the same, which arc is generated by high frequency alternating currents.

Still another object of my invention is the provision of a method for preventing the concentration of an arc or electrical discharge when operated between electrodes having adjacent surfaces arranged parallel with respect to each other.

Other objects of my invention will be apparent from the following description.

In lamps which are adapted for the projection of motion pictures, it is desirable to provide a concentrated light source and heretofore it has been the practice to provide such a source by arranging two sets of series connected coils, one set being positioned behind the other and out of alignment therewith so that the second set of coils fills the interstices or spaces between the elements of the first set in order that the light might be as uniform as possible and constitute a solid light source. In a lamp of this type, special supporting arrangements were necessary in order to prevent the filament from breaking or becoming distorted. Furthermore, in order to avoid the reversed image of the filament appearing on the screen, the light source was placed out of focus with the films which resulted in decreased efficiency.

In the present construction, which forms the subject of my invention, I have provided a lamp in which the light giving source is supported in a simple manner, and furthermore constitutes a solid body. In the accompanying drawing, the view therein illustrates one embodiment of my invention and also shows connected to the lamp, a source of high frequency current.

The lamp bulb 1 may be of any suitable form and is indicated as of spherical construction. Mounted within the bulb and arranged centrally with respect thereto are electrodes 2 and 3, each of which consists of a disk, of circular or other desired shape, of a refractory metal or other incandescent material, such as tungsten, carbon and the like. These electrodes are so arranged that they lie in planes parallel to each other for a purpose to be brought out more fully hereinafter. Each of the electrodes is connected by leading-in wires 4 and 5, respectively, to the opposite poles of the secondary of a transformer. These leading-in wires serve to support the electrodes 2 and 3 and are disposed within the lamp substantially in the plane of the electrodes so that they do not interfere with the passage of light given off by the electrodes 2 and 3. A seal 6 is provided at each of the points where the electrodes pass through the walls of the glass bulb and a re-enforcing sleeve 7 surrounds the leading-in wires to furnish additional stability. Obviously, the leading-in wires may be otherwise arranged and the electrodes may be suitably supported independently thereof if desired.

The electrodes 2 and 3 may be of any desired configuration, it being a requisite, however, that they have at least their contiguous faces in substantial parallelism. The container or bulb 1 is filled with a gas inert with respect to the electrode material, such gas being nitrogen, argon, neon, helium and the like, or mixtures of these gases. The pressure of the gas within the envelope may be from one-third to one-half of an atmosphere, that is, it should be capable of sustaining an arc or electrical discharge between the electrodes.

I have discovered that in order to pro-

vide for uniform heating of the electrodes by means of an arc or electrical discharge and in order to prevent concentration of the arc or electrical discharge at any point between the electrodes that if the arc or electrical discharge is sustained by a high frequency current, the frequency being in the neighborhood of 30,000 and up, that the arc or electrical discharge will be uniformly distributed between the electrodes, thus providing for uniform disk illumination. The high frequency energy may be supplied by any well known means and in the drawing there has been illustrated a form of Tesla high frequency transformer for supplying such a current. The high frequency current may be produced as follows: A low frequency alternating current is furnished by the generator 8, which current is stepped up by a transformer 9 consisting of a primary 10 and secondary 11. The latter has one of its ends connected to one end of a primary coil 14 and the other end to the primary coil through a spark gap 13. In this circuit is provided a capacity 12 for a purpose which is obvious. The high frequency current set up in the primary 14 is stepped-up by the adjustable secondary 16. The secondary 16 is connected by conductors 17 and 18 to the leading-in wires 6 and 7, respectively.

In the operation of the device, the low-frequency alternating current from the generator 8 is stepped-up by transformer 9, converted into high frequency current by the oscillating circuit 12, 13, 15 and stepped up by the Tesla transformer 14 into high frequency alternating current which high frequency current is supplied to the lamp. The current passes between the electrodes 2 and 3 and is uniformly distributed therebetween in the form of an arc or electrical discharge by reason of the high frequency of the current.

While I have shown means for supplying high frequency alternating current to the terminals of the lamp, it is to be understood that other suitable forms of high frequency current, such as high frequency oscillating currents, may equally well be used.

I have found that a lamp of this character cannot be operated on a low voltage D. C. or A. C. current for the simple reason that the arc or electrical discharge would concentrate on some spot on the disk and give non-uniform temperature thereof. By utilizing the high frequency, apparently the arc or electrical discharge is prevented from concentrating at such spots and is distributed uniformly between the disks. In order that this uniform distribution may be had, it is desirable to have the disks or electrodes with their contiguous faces in substantial parallelism.

It will be obvious to those familiar with the disadvantages resident in the present

type of motion picture lamp that my lamp overcomes the same by providing a solid, uniformly heated body which gives a constant and steady source of illumination.

Many modifications of my invention may be made and therefore I do not wish to be restricted to the particular embodiment shown in the drawing and described herein.

What is claimed is:

1. The method of preventing an arc discharge operated between electrodes of relatively large area from concentrating which comprises generating the arc discharge by means of high frequency current. 75

2. The method of uniformly heating electrodes of relatively large area by an arc discharge therebetween which comprises generating the arc discharge by high frequency current. 80

3. The method of producing light by high frequency current which comprises applying said current between two electrodes having adjacent surfaces of relatively large area in substantial parallelism and providing an arc discharge-sustaining media between said electrodes. 85

4. In an incandescent lamp, an envelope having an arc discharge-sustaining media therein, electrodes within said envelope, said electrodes having adjacent surfaces in substantial parallelism, and means for conducting high frequency current to said electrodes, whereby an arc discharge is uniformly distributed therebetween. 95

5. In an incandescent lamp, an envelope having an electrical discharge-sustaining media therein, electrodes within said envelope, at least one of said electrodes consisting of a refractory substance, said electrodes having adjacent surfaces in substantial parallelism, and means for impressing an electrical discharge between said electrodes by high frequency current. 100

6. In an incandescent lamp, an envelope having an electrical discharge-sustaining media therein, electrodes within said envelope, said electrodes consisting of refractory substances, and having adjacent surfaces in substantial parallelism, and means for impressing an electrical discharge between said electrodes by high frequency current. 110

7. In an incandescent lamp, an envelope having an arc discharge-sustaining media therein, electrodes within said envelope consisting of tungsten, said electrodes having adjacent surfaces in substantial parallelism, and means for impressing an arc discharge between said electrodes by high frequency current. 120

8. In an incandescent lamp, an envelope having an arc discharge-sustaining media therein, a pair of electrodes, each consisting of a plate of a refractory substance, said electrodes being arranged with their adjacent surfaces in substantial parallelism, 125

and means for impressing an arc discharge between said electrodes by high frequency current.

9. In an enclosed arc luminous electrode device, an envelope having an arc discharge-sustaining media therein, a pair of electrodes within said envelope, each of said electrodes consisting of a disk of refractory material,

said disks being arranged in substantial parallelism, and means for sustaining an arc discharge between said electrodes by high frequency current.

In testimony whereof, I have hereunto subscribed my name this 19th day of February, 1923.

HARVEY CLAYTON RENTSCHLER.
